United States Patent Office.

WILLIAM BRIGGS, OF BRISTOL, RHODE ISLAND, ASSIGNOR TO HIMSELF
AND THOMAS HOLMES, OF SAME PLACE.

Letters Patent No. 65,159, dated May 28, 1867.

IMPROVED MOLASSES-VESSEL.

The Schedule referred to in these Letters Patent and making part of the same.

Be it known that I, WILLIAM BRIGGS, of Bristol, in the county of Bristol, and State of Rhode Island, have invented new and useful improvements in Vessels for Holding Molasses or Sirup for household use; and I do hereby declare the following to be a full and correct description thereof, reference being had to the accompanying drawings, forming part of this specification, and to the letters of reference marked thereon.

The drawing is a perspective view of the pail with the cover raised.

A represents the pail, which is made of wooden staves and hooped in the usual way, and is of a suitable height to be conveniently set between two closet-shelves. D is a cover, turned to fit closely in top of the pail, which is also furnished with a bail, C. A gate, O, is placed in the side near the bottom. a is an arm or guard, one end of which is pivoted to the top of the flange of the gate, and fitting into a notch in the handle of the gate. This is to prevent the gate from being opened accidentally, as it is liable to be. The dotted line a' shows the position of the guard when the gate is to be opened.

This vessel is intended to obviate the objections to, and supply the deficiencies of, the various receptacles now used for the purpose of holding molasses or sirup for household use. By means of the movable cover the inside can be reached, and the deposit of sugar, &c., that collects at the bottom can be removed, which obviates the greatest objection there is to a keg with a gate, which latter is liable to be choked up by the deposit of sugar, &c., which cannot be readily removed. The objection to the use of a tin vessel for the purpose is its liability to be eaten through by the acid in the molasses; and an earthen jug is both heavy to carry and unhandy to fill and to empty, and liable to be broken. All these objections are overcome in this pail, which is readily filled without a tunnel at a considerable saving of time and material, is light and handy to carry, and can be made at a reasonable cost. Its operation or use needs no description, as it is obvious that it is filled at the top and drawn from the gate when required.

I claim as a new article of manufacture, a pail or bucket constructed and furnished as herein described, in combination with the gate O, as herein set forth, and for the purpose specified.
